UNITED STATES PATENT OFFICE.

HENRY S. GERMOND, JR., OF BAYONNE, NEW JERSEY.

ELEVATING TRUCK.

Application filed May 5, 1926. Serial No. 106,858.

This invention relates in general to elevating trucks of the type including a main frame mounted on wheels and adapted to be moved about and steered by a draft handle and pushed beneath a load which is to be transported, said main frame carrying an elevating platform adapted to be raised by swinging of the draft handle in a vertical plane to elevate the load from the floor. 10 More particularly, the invention relates to that type of elevating trucks including a member movable substantially vertically in or parallel to the axis of swivel of the steering wheels, said member being adapted to be so connected to the draft handle as to elevate the platform by swinging of the handle in vertical planes with the handle in any of the usual steering positions at angles to the longitudinal median line of the truck. 15 One object of the invention is to provide a truck of the character described embodying a novel and improved actuating mechanism for raising said platform by means of said draft handle including a member vertically movable substantially in the line of axis of the steering swivel and connected to said draft handle, and means for connecting said vertically movable member to said platform to raise the latter while said handle is in any 20 usual steering position.

Another object of the invention is to provide a device of the character described embodying novel and improved features of construction whereby descent of the elevating platform cannot take place until said vertically movable member has been disconnected from said platform, so as to prevent possibility of the handle being accidentally forcibly swung upwardly by descent of the 25 platform and injuring the operator.

Other objects are to provide in an elevating truck of the character described novel and improved manually operated means for connecting and disconnecting the platform to and from said vertically movable member; to provide means whereby said platform can be connected to or disconnected from said vertically movable member while the handle is in any of the usual steering positions; 30 to provide a simple, inexpensive and reliable construction, and to obtain other results and advantages as may be brought out by the following description.

Referring to the accompanying drawings,

in which corresponding and like parts are designated throughout the several views by the same reference characters,

Figure 1 is a side elevation of an elevating truck embodying the invention, showing the elevating platform in its normal lowered position;

Figure 2 is a fragmentary side elevation of a front end of the truck, showing the elevating platform arranged in its uppermost position;

Figure 3 is an elevation of the front end of the truck, showing the manner of elevating the platform from one side of the truck, and

Figure 4 is a fragmentary top plan view 70 of the front end of the truck.

In the specific embodiment of the invention shown on the drawings, the reference character A designates the frame of the truck which may be of any suitable construction and is mounted at the rear end on wheels 1 journaled on a transverse shaft 2 (see Fig. 1). The forward end of the frame A is provided substantially centrally of its width with a king pin 3 revolubly journaled 75 in the frame and carrying at its lower end a pair of steering wheels 4, this construction enabling the truck to be steered by rotation of the king pin 3.

An elevating and load sustaining platform B is mounted on the frame A in such a manner that the truck may be pushed beneath a load which is spaced from the floor by means of skids, the said platform being adapted to be elevated on the frame A to 85 raise the load from the floor onto the truck. Any suitable means may be utilized for so mounting the platform on the same, but in the present instance a pair of parallel links 5 is shown as pivotally connected between 90 the frame A and the platform B at each end so that forward motion of the platform causes oscillation of the parallel links 5 which in turn raises the platform on the main frame. All of the above-mentioned 95 construction is old and well-known, and no claim to novelty is based thereon.

For the purpose of drawing the truck from place to place and steering the same, the king pin 3 may have secured thereto a 100 bracket 6 formed with two upwardly projecting spaced ears 7 between which is pivotally mounted between its ends on a pin 8

a draft handle 9, said handle being adapted to swing about its pivot 8 in vertical planes and to revolve the king pin 3 by swinging of the handle in horizontal planes so as to 5 steer the truck. The handle is provided at one end with handholds for drawing the truck and said handle is also adapted to be operatively connected with the platform B to draw the same forwardly so as to oscillate 10 late the links 5 and elevate the platform.

A sleeve 11 is slidably mounted on the king pin 3 above the frame A and is provided at its lower end with a substantially semi-circular flange 12 having an upwardly 15 facing groove 120 to cooperate with a hooked end 13 on one end of a link 14 pivotally connected at its other end to the forward end of the platform B. The end of the draft handle opposite the handholds is pivotally 20 connected as at 15 to one end of a link 16 the other end of which is pivotally connected to an ear 17 on the upper end of the sleeve 11. The link 14 may be connected to the forward end of the platform 25 in any suitable manner, but in the present instance I have shown the link connected to the front side of a skid stop 18 which forms the forward end of the platform B and is adapted to engage a skid to limit the movement 30 of the truck beneath the skid bearing a load which it is desired to elevate and transport by the truck.

When the platform B is in its normal lowermost position, the link 14 is swung rearwardly into a substantially vertical position against the skid stop 18, as shown by solid lines in Figure 1, and in this position the handle 9 is free for drawing and steering the truck. When it is desired to elevate the platform B, the handle 9 is swung upwardly into a substantially vertical position, as shown in Figure 1, which lowers the sleeve 11 to the top of the frame A after which the link 14 is manually swung forwardly, for instance by the foot of the operator, so that the hook 13 lies in the groove 120 of the sleeve. The handle 9 is then swung downwardly in a vertical plane, as indicated by Figure 2, whereby the sleeve 55 11 is raised upon the king pin 3 and the platform B pulled forwardly and elevated by oscillation of the links 5.

Any suitable means may be employed for holding the elevating platform in its uppermost position, but in the present instance I have shown the forward end of the platform B provided with a rearwardly facing lug 19 adapted to be engaged by the head 20 of a latch lever 21 pivotally mounted intermediate 60 its ends as at 22 on the forward end of the main frame A. The latch lever 21 is normally influenced into the path of the lug 19 by means of a spring 23, and as the platform B rises, the lug 19 slips beneath the head 20 of the lever 21, which then engages

the rear face of the lug to hold the platform against rearward movement and descent. The platform is shown in its uppermost position in Figure 1 of the drawings, and may be steered under ordinary conditions without 70 throwing the link rearwardly, due to the lateral play between the groove 120 and hook 13. After the platform has been raised to this position and it is desired to lower the platform, it is advisable to disconnect 75 the link 14 from the sleeve 11, and this disconnection is readily accomplished by swinging the handle 9 upwardly into the position shown in Figure 1 and then pushing the link rearwardly into contact with the skid stop 18. To release the platform the forward 80 end of the latch lever 21 is provided with a treadle 24 which may be depressed by the operator so as to disengage the head 20 of the lever from the lug 19 whereupon the platform descends by action of gravity. Any known means, such as a dash-pot construction, may be utilized to retard the descent of the platform.

For preventing operation of the latch lever 21 and descent of the platform B until the link 14 has been completely disconnected from the handle 9, whereby the possibility of the handle being forcibly swung upwardly by descent of the platform in such a manner as to injure the operator, is obviated, I may provide a gravity actuated pawl 25 pivotally connected at one end 26 to the forward end of the platform B, for instance to the skid stop 18, above the lug 19, the lower end of said pawl being normally positioned by action of gravity to engage the top of the head 20 of the latch lever 21 when the platform is in its uppermost position and the link 14 connected to the handle 9. The pawl 25 is shown in operative relation to the lever 21 in Figure 2, and it will be obvious that with the pawl in this position the lever 21 cannot be oscillated by pressure on the treadle 24.

To automatically release the lever 21 when the link 14 is disconnected from the handle 9, I may provide the link 14 with a laterally projecting lug 27 adapted to engage a similar lug 28 on the adjacent side of the pawl 25, so that as the link 14 falls rearwardly to its inoperative position, the lug 27 engages the lug 28 and swings the pawl 25 rearwardly out of engagement with the latch lever 21, as shown in Figure 1. With the pawl 25 in this position, the latch lever 21 may be freely operated so as to permit descent of the platform B, but it will be observed that there is no possibility of the handle 9 being swung upwardly, since the pawl 25 is caused to release the lever 21 only after the link 14 has been completely disconnected from the handle 9.

Under some conditions the load on the platform B is so close to or so overhangs the

skid stop 18 as to render it difficult or impossible for the operator to reach the link 14 with his foot to pull it forwardly into engagement with the flange 12. To overcome this difficulty, I may provide the upper end of the pawl 25 with an upwardly and forwardly projecting treadle 29 so arranged as to be always accessible to the operator. With such a construction the link 14 may be thrown forwardly by merely pressing the treadle 29 rearwardly, the pawl 25 being thus swung on its pivot so that the lug 28 in engagement with the lug 27 on the link pushes the link forwardly as desired. This construction is further advantageous in that it is easier to push rearwardly on the treadle 29 than to pull forwardly on the link 14. To further facilitate in pulling the link 14 forwardly, a lateral arm 30 may be provided on the link to be engaged by the foot of the operator.

It will be observed that a truck constructed in accordance with the invention permits the elevating platform to be raised upon the main frame by oscillation of the handle 9 in vertical planes and in any of the usual steering positions of the handle, for instance as indicated in Figure 3 of the drawings, where the handle is shown to swing in a plane at substantially right angles to the longitudinal median line of the truck. Furthermore, the platform can be easily and quickly connected to and disconnected from the draft handle by mere swinging of the link 14.

While I have shown and described the invention as embodied in certain details of construction, it will be understood that this is primarily for the purpose of illustrating the invention and that many modifications and changes may be made in said details without departing from the spirit or scope of the invention. Therefore, I do not desire to be understood as limiting myself except as required by the following claims when construed in the light of the prior art.

Having thus described the invention, what I claim is:

1. An elevating truck comprising a main frame mounted on wheels at its rear end, a steering swivel carrying wheels journaled in the front end of said frame, a rotatable member movable vertically in substantially the line of axis of said steering swivel and having a horizontal coaxial arcuate flange, an elevating platform mounted on said frame for vertical movement, means operatively connecting said flange of said member and said platform so that vertical movement of said member elevates said platform and said member may rotate independently of said connecting means, a handle pivotally mounted upon said swivel, and an operative connection between said handle and said member so that swinging of said handle in

vertical planes in any of the steering positions of said handle raises and lowers said member.

2. An elevating truck comprising a main frame mounted on wheels at its rear end, a steering swivel carrying wheels journaled in the front end of said frame, a member vertically movable in substantially the line of axis of said steering swivel and having a horizontal coaxial arcuate flange, an elevating platform mounted on said frame for vertical movement, means operatively connecting said flange on said member and said platform so that the platform is elevated as said member is raised and rotation of said member relatively to said means is permitted, a draft handle pivotally mounted intermediate its ends on said steering swivel, and a link pivotally connected to one end of said handle and to said member so that as the handle is swung downwardly said member is raised and said platform is elevated and the platform may be elevated with the handle in any steering position.

3. An elevating truck comprising a main frame mounted on wheels at its rear end, a steering swivel carrying wheels journaled in the front end of said frame, a member vertically movable in substantially the line of axis of said steering swivel, an elevating platform mounted on said frame for vertical movement, a link pivotally connected at one end to said platform, the other end of said link and said vertically movable member having cooperating portions to engage each other so that raising of said member elevates said platform, said cooperating portions having a relatively slidably engagement in the same horizontal plane of said member at any point in the vertical movement thereof so that said member may rotate relatively to said link, a handle pivotally mounted upon said swivel, and an operative connection between said handle and said member so that swinging of said handle in vertical planes in any of the steering positions of said handle raises and lowers said member.

4. An elevating truck comprising a main frame mounted on wheels at its rear end, a steering swivel carrying wheels journaled in the front end of said frame, a member vertically movable in substantially the line of axis of said steering swivel and having a coaxial upwardly facing arcuate recess, an elevating platform mounted on said frame for vertical movement, means operatively connecting said platform and said movable member including a hook arranged in said recess so that raising of said member elevates said platform and said member can rotate relatively to said connecting means, a handle pivotally mounted upon said swivel, and an operative connection between said handle and said member so that swinging of said handle in vertical planes in any of

the steering positions of said handle raises and lowers said member.

5. An elevating truck comprising a main frame mounted on wheels at its rear end, a king pin journaled in the front end of said frame and carrying wheels for steering the truck, an elevating platform mounted on said frame for vertical movement, a sleeve vertically slideable on said king pin having an arcuate flange provided with an upwardly facing arcuate groove, a link having one end pivotally connected to said platform and formed at its other end with a hook to enter said groove so that raising of said sleeve will elevate said platform and said sleeve may rotate relatively to said hook, a handle pivotally mounted intermediate its ends upon said king pin, and an operative connection between said sleeve and said handle so that swinging of the handle in vertical planes raises and lowers said sleeve.

6. An elevating truck comprising a main frame mounted on wheels at its rear end, a king pin journaled in the front end of said frame and carrying wheels for steering the truck, an elevating platform mounted on said frame for vertical movement, a sleeve vertically slideable on said king pin having an arcuate flange provided with an upwardly facing arcuate groove, a link having one end pivotally connected to said platform and formed at its other end with a hook to enter said groove so that raising of said sleeve will elevate said platform and said sleeve may rotate relatively to said hook, a handle pivotally mounted intermediate its ends upon said king pin, and a link connected to said sleeve and said handle so that swinging of the handle in vertical planes raises and lowers said sleeve. 30 35
